Inventor:

Harry J. Kusel,

By A. Allen Belfield Atty.

UNITED STATES PATENT OFFICE.

HARRY J. KUSEL, OF CHICAGO, ILLINOIS, ASSIGNOR TO STRONGHEART COMPANY, OF CHICAGO, ILLINOIS, A CORPORATION OF ILLINOIS.

COIN BANK.

Application filed June 26, 1920. Serial No. 391,935.

To all whom it may concern:

Be it known that I, HARRY J. KUSEL, a citizen of the United States, residing at Chicago, in the county of Cook and State 5 of Illinois, have invented a certain new and useful Improvement in Coin Banks, of which the following is a full, clear, concise, and exact description, reference being had to the accompanying drawings, forming a 10 part of this specification.

My invention relates to coin banks, and particularly to a form thereof known as "registering" banks, for registering the number of coins and consequently the 15 amount of money in the bank.

The object of the invention is to provide a simple and practical form of registering coin bank.

Another object of the invention is to permit 20 the bank to be readily opened to permit the removal of the coins and also to be effectively located to prevent unauthorized removal of the same.

Another object of the invention is to provide 25 a construction which will permit the banks being made in large numbers at low expense.

In the accompanying drawings Fig. 1 is a side elevation of a registering coin bank 30 embodying my present invention;

Fig. 2 is an end elevation of the same;

Fig. 3 is a longitudinal section of the bank on an enlarged scale;

Fig. 4 is a cross section taken on line 4—4 35 in Fig. 3;

Fig. 5 is a horizontal section taken on line 5—5 in Fig. 3.

Referring to the drawings I show a bank A, preferably made in somewhat oval shape 40 body 1, as best shown in Fig. 5, and with a flat top 2 and flat bottom 3. The body 1 is preferably made of a sheet metal band bent to the proper shape and having its meeting edges 1^a—1^b (Fig. 5) secured together by a

45 metal disc 5, which is secured to the opposite sides of said band by means of rivets 6—6. The metal disc 5 may be circular in form and made, if desired, to be used as a name plate, to bear the name and location of the 50 banking institution putting out the coin bank, and also, if desired, some advertising or thrift suggesting matter.

The top 2 of the bank carries a member 8 which is so constructed as to provide with

the casing 1 two coin chambers 9—9, one 55 at each end of the oval body. This member 8 has a central body portion 10, with cylindric curved surfaces or walls 11—11 having substantially the curvature of the opposite ends of the body 1, so that the chambers 9 60 are substantially circular in cross section so as to accommodate the coins. The body 10 is preferably made of two parts 10^a and 10^b, secured firmly together, as by grazing, to 65 make a single solid member.

The member 8 is secured to the top 2 as by means of rivets 14—14 and the top 2 is removably fitted over the top of the casing 1, as by providing said top 2 with an overhanging lip or edge 15. The top 2 being removable from the body 1, the member 8 secured to the top 2 is also removable with said top and accordingly is arranged to slide in and out of the casing 1. This removable arrangement, however, is more for 70 purposes of construction and repair than for purposes of operation in the ordinary use of the bank. The member 8 is also provided with a centrally arranged well or recess 16 located between the coin chambers 80 9—9. The lower end of this well 16 is provided with a partition 17 having a similar aperture 18 adapted to accommodate a screw or bolt 19, the purpose of which will be hereinafter pointed out. The top 2 is provided 85 with an aperture 20 coinciding with the well 16 so as to afford communication between the well 16 and the outside of the bank.

The bottom 3 is also arranged to fit removably or detachably on the lower end of the body or casing 1, and is to such extent provided with an upwardly projecting rim or lip 21. As an arrangement for locking the bottom 3 temporarily in place, a lug or clip 24 is secured to the bottom 3 as by rivets 25, 95 (Fig. 4) and this clip 24 is provided with a threaded aperture adapted to receive the threaded end of the bolt 19. The bolt 19 may be turned by means of a key inserted in the well 16, the bolt 19 and the key having cooperating engaging members, as for example, by providing the bolt 19 with a triangular head 26 and the key with a correspondingly shaped socket. Thus by using the unlocking key 27 shown in dotted lines 100 in Fig. 3, the bolt 19 may be unscrewed, thereby unlocking the bottom 3 and permitting the same to be removed by the hand. 105

In order to lock the bottom 3 in position, the bolt 19 is turned so as to screw it into the lug 24.

In using the bank the two chambers 9—9
5 are usually filled with coins and then the bottom 3 is removed so as to permit the removal of the coins. The coins simply fall out of the bank, leaving the open bottoms of the chambers 9, the member 10 adhering
10 to the top 2. This makes a very simple arrangement, it being necessary only to unlock and remove the bottom 3, in order to empty the bank. After it is emptied, the bottom 3 is again placed and locked in position and the bank again filled more or less
15 with coins, as desired.

In order that it may be known just how many coins there are in the bank, the ends of the casing 1 are preferably provided with
20 indicating slots 28—28 below the coin slots 1^b, and these slots 28 are preferably at an inclination, as shown in Fig. 2, so that the coins may be seen to best advantage. These inclined slots are disclosed and claimed in
25 application No. 363,013, filed March 3, 1920, by Isidor J. Kusel, for coin bank, and hence are not claimed herein.

It will be understood that changes and modifications may be made without departing from the spirit of the invention.

What I claim is:

1. A coin bank having a casing provided with an interior member dividing the casing into coin chambers open at their lower
35 ends, said casing having a removable bottom, and means for locking the bottom in position to close the chambers, said means being operable through the top of the bank.

2. A coin bank having a casing provided
40 with a removable bottom an interior member dividing the interior of the casing into coin compartments open at their lower ends, said interior member having a recess or well extending downwardly from the top of the
45 bank, and means detachably connecting said interior member to the removable bottom so as to lock the bottom in position closing the lower end of said compartments.

3. A coin bank having a casing provided
50 with a removable bottom an interior member dividing the interior of the casing into coin compartments open at their lower ends, said interior member having a recess or well extending downwardly from the top of the
55 bank, and means at the bottom of said well or recess for locking the bottom of the bank

in position to close the open lower ends of said compartments, said means comprising a threaded bolt.

4. A coin bank comprising an oblong casing having a flat top and flat bottom, said bottom being detachable from the bank, a member inside of the bank for dividing the interior into coin chambers open at their lower ends, said member being secured to
60 the top, and means operable through the top of the bank for detachably securing the bottom to said member so as to close the open lower ends of the chambers.

5. A coin bank comprising an oblong casing having a flat top and flat bottom, said bottom being detachable from the bank, a member inside of the bank for dividing the interior into coin chambers open at their lower ends, said member being secured to
70 the top, and means operable through the top of the bank for detachably securing the bottom to said member so as to close the open lower end of the chambers, said member comprising a screw bolt passed through
75 an aperture in the member and engaging a threaded socket with which the bottom is provided.

6. A coin bank comprising an oblong casing having a flat top and flat bottom, said bottom being detachable from the bank, a member inside of the bank for dividing the interior into coin chambers open at their lower ends, said member being secured to
85 the top, and means operable through the top of the bank for detachably securing the bottom to said member so as to close the open lower end of the chambers, said member comprising a screw bolt passed through
90 an aperture in the member and engaging a threaded socket with which the bottom is provided, said screw bolt being located at the bottom of a well formed in the central portion of said interior member.

7. A coin bank comprising a casing provided with an interior member forming coin chambers which are open at their lower ends, a detachable bottom for closing and opening the open lower ends of said coin chambers, and locking means for temporarily locking the bottom in position to close the lower ends of the coin chambers, said locking means operable through the top of the bank.

In witness whereof, I hereunto subscribe my name this 7th day of June A. D. 1920.

HARRY J. KUSEL.
